UNITED STATES PATENT OFFICE.

EUGÈNE LOUIS EZBELENT, OF PARIS, FRANCE.

PLAITING MACHINE.

Original application filed August 31, 1925, Serial No. 53,705, and in France June 15, 1925. Divided and this application filed October 19, 1926. Serial No. 142,708.

The machines in current use for the obtaining of plaited work comprise an upper and a lower plaiting blade which are continuous and have the same length as the machine. The movements of the two blades are combined, and they will produce either overlapping knife plaits or under-lapping knife plaits, according as they are made to follow one of two plates respectively termed 5 "upper formation plate" or "lower formation plate"; they will further produce box plaits when they are made to follow alternately the said upper and lower plates. In all cases, by virtue of the continuous form of 10 the plaiting blades, the plaits or folds will be of the same character over all the length of the fold.

My invention, which is a division of my pending application No. 53,705 filed August 20 31, 1925, has for its object an improved plaiting machine affording the obtaining of patterns, designs and folds which are reversed in the lengthwise direction of the fold. Said machine is chiefly characterized 25 in that it comprises a plurality of pivoted plaiting blade elements disposed upon the length of the machine, and that certain of the said elements may be given different movements relatively to the others.

30 Various other features of the invention will be set forth in the following description with reference to the appended drawings, given by way of example, and relative to an embodiment of the said invention.

35 Fig. 1 is a section of the machine with the plaiting blades in the front position, and

Fig. 2 is a like view with the plaiting blades in contact with the formation plates.

40 The upper blade elements 14' are secured to the blade carriers 40 rotatable upon a shaft or tube 41 constituting the upper frame of the machine. The lower blade elements 14 are secured in like manner to the blade carriers 42 mounted on the shaft or tube 43 constituting the lower frame of the machine. The lower frame, that is the tube 43, carries at each end two standard plates 4 in which the upper frame, that is the tube 41, is adapted to rotate. The plates 45 50 are provided with journals 6 which are given a straight reciprocating motion towards and away from the cylinders as usual for the blade of plaiting machines.

A C-shaped member 7 is secured to the 55 tube 41 and is supported through the me-

dium of a roller 8 upon a plate 9 which may be raised during the rearward stroke away from the cylinders of the journals 6 and of the tubes 41 and 43, as usual in well-known plaiting machines. This will provide for 60 the rotation of the tube 41. The spring 20 urges each upper plaiting blade element to rotate about the tube 41 and causes said upper blade element to enter into contact with a lower plaiting blade element. In this 65 manner, each upper element will cause the opposite lower element to descend when the latter is not controlled, and when the said lower element is controlled, it will in turn cause the upper element to rise. The lower 70 frame or tube 43 is adapted to receive an oscillating rotation by controlling means not represented and generally used in the known plaiting machines.

75 The carriers 42, rotatable on the tube 43, are each provided with a pin or stud 46 extending and adapted to slide through the same; said stud is urged outwardly by a spring 47, and when the latter is compressed, the stud may engage in a corresponding 80 aperture 48 in the tube 43. When the stud is in the position shown in Fig. 1, the corresponding blade element will be loose on the tube. The corresponding upper blade carrier 40, which is urged into its lower position 85 by the spring 20, will oblige the lower blade element to assume its lower position, thus providing for the formation of an under-lapping plait.

90 The insertion of the studs 46 into the tube 43, for connecting together the said tube and the blade carrier 42, is controlled by cam elements or bosses 37 disposed in circular rows upon a rotary drum 36 to which a continuous or intermittent motion may be imparted; 95 each row of cam elements corresponds to one pin or stud 46, and the cam elements of one row may control the inward motion of the corresponding pin 46 through the medium of a rocking arm 32 mounted loose on a 100 common shaft 33 and provided with a roller 34 situated in the same plane as the cam elements 37. Each of the latter may be removably secured upon the drum for instance by means of a shank adapted to engage a 105 hole provided in the periphery of the drum.

110 The drum may be given an intermittent rotary motion, so that it is rotated through half the angular space between two consecutive holes of one row at the end of the for-

ward and rearward strokes of the lower frame, each hole, or the cam element engaged therein, being in line with the roller 34 of the corresponding arm 32 during the forward 5 stroke of said lower frame.

When a boss 37 engages the roller 34 of one lever 32, the latter will be raised, thus causing the stud 46 to enter the recess 48 in the tube 43. The corresponding blade element 10 42 is thus connected by the stud with the tube 43 and will hence follow the movements of the latter and will produce either overlapping plaits or underlapping plaits. If there 15 are no bosses engaging the roller 34, the corresponding blade element will produce an underlapping plait.

I am thus enabled to modify the nature of the folds made by each blade element during the course of the work, without stopping the 20 machine, by inserting or withdrawing the corresponding boss 37.

Fig. 2 shows blade carriers 42^a which are connected by their studs with the tube 43 and thus are in a position corresponding to the 25 formation of overlapping plaits, and other blade carriers 42^b, which are loose on the tube 43 and are in a position corresponding to the formation of underlapping plaits.

It will be observed also that upon the 30 whole length of the tube 41 is a groove 44 in which engage stop screws 45 respectively carried by the blade carriers 40. When the "C" device rotates the tube 41, the latter will drive at a certain moment, the screws 45 35 of all the blade elements, so that the latter will be opened. The said groove 44 has sufficient width so that when the "C" device is inoperative, the blade elements may assume the upper or the lower position.

40 Obviously, I may substitute for the drum with removable bosses, a band, for instance of cardboard, which is either perforated or is provided with removable bosses, and which is movable below the control levers, thus 45 serving the same purpose as the above described drum.

Having now described my invention, what I claim as new and desire to secure by Letters Patent is:

50 1. In a plaiting machine the combination with two pressing drums and with the upper and the lower longitudinal frames, of two sets of plaiting blade elements rotatably mounted on said frames and means whereby 55 the blade elements of said lower frame are intermittently secured and unsecured to their shaft during the forward stroke of said lower frame for the purpose set forth.

2. In a plaiting machine the combination

with two pressing drums and with the upper 60 and the lower longitudinal frames, of two sets of plaiting blade elements rotatably mounted on said frames, spring controlled studs respectively adapted to secure to the lower frame the plaiting blade elements 65 mounted on said lower frame, and normally out of engagement with said frame, and means whereby said studs are caused to engage said frame, and thereby secure said latter plaiting blade elements to the same during 70 the forward stroke of said lower frame for the purpose set forth.

3. In a plaiting machine, the combination with two pressing drums and with the upper and the lower longitudinal frames, 75 of two sets of plaiting blade elements rotatably mounted on said frames, spring controlled studs respectively adapted to secure to the lower frame the plaiting blade elements mounted on said lower frame, and 80 normally out of engagement with said frame, a support adapted to be moved in front of said studs and rows of cam elements respectively corresponding to said 85 studs and mounted on said support according to a predetermined disposition and whereby said studs are caused to engage said corresponding frame and thereby secure said latter plaiting blade elements to the same, during the forward stroke of said 90 lower frame.

4. In a plaiting machine the combination with two pressing drums and with the upper and the lower longitudinal frames, of two sets of plaiting blade elements rotatably mounted on said frames, a longitudinal groove in the periphery of the upper frame, 95 studs respectively provided on the plaiting blade elements mounted on said upper frame and engaging said groove, yielding means whereby each of the plaiting blade elements mounted on said upper frame are constantly urged towards the opposite plaiting blade elements mounted on the lower frame, and means whereby each of said latter plaiting blade elements may be brought at will into its lower position and into its 100 upper position for the purpose set forth.

5. In the combination as claimed in claim 4, the further feature residing in that the 110 width of said groove is such that when said upper frame is stationary the plaiting blade elements carried thereby may assume their upper or their lower position.

In testimony whereof I have signed my 115 name to this specification.

EUGÈNE LOUIS EZBELENT.
